UNITED STATES PATENT OFFICE.

TETSUTARO IKEMORI, OF SAN FRANCISCO, CALIFORNIA.

CAN-OPENER.

1,288,419.

Specification of Letters Patent.

Patented Dec. 17, 1918.

Application filed February 26, 1918. Serial No. 219,302.

To all whom it may concern:

Be it known that I, TETSUTARO IKEMORI, a subject of the Emperor of Japan, residing at San Francisco, in the county of San Francisco and State of California, have invented new and useful Improvements in Can-Openers, of which the following is a specification.

The object of the present invention is to provide a device for punching a hole in the top of a can for pouring out the contents thereof so constructed that the hole so punched will be in the form of a spout so as to permit the liquid contents of the can to flow therefrom in a coherent stream without the spreading or spattering which occurs when the liquid flows through an ordinary round hole.

In the accompanying drawing, Figure 1 is a front view of my improved can opener; Fig. 2 is a side view thereof; Figs. 3, 4, 5 are enlarged vertical sections, showing different stages in the operation of punching the hole; Fig. 6 is an enlarged horizontal sectional view of a portion of a can showing the form of the hole punched therein; Fig. 7 is a perspective view of a top of a can, also showing the hole.

Referring to the drawing, 1 indicates a body of a can opener formed of hard wood or any other suitable material. Said body comprises a comparatively wide upper portion 2 and a narrow lower portion 3 with which the upper portion 2 forms a horizontally extending shoulder 4. Driven into the shoulder 4 is a cylindrical punch 6 preferably of steel or other hard metal and having a conical and pointed lower end 7. Said punch extends in a direction in general parallel with the narrow portion 3 of the body but is slightly curved outwardly downward. The narrow portion 3 of the body terminates downwardly in a rounded enlargement or boss 8 on the side next the punch, the surface of which boss nearest to the punch engages the outside of the round surface of the can close to its top while the punch itself penetrates the top of the can close to its edge.

The rounded surface 9 of the boss 8 lying adjacent to the point of the punch is formed with a vertically extending groove 11 of slightly greater width than the diameter of

the punch. This groove forms the novel feature of my invention. By means thereof when the pointed end 7 of the punch penetrates the top of the can close to its edge, and the outer portion of the metal of the can is, pressed outwardly by the descent of the conical end of the punch through the top of the can said outer portion is pressed into a spout-like aperture 12. Thus the liquid contents of the can can be poured out without spreading or spattering.

The slightly curved form of the punch has the effect of drawing the body of the can opener toward the can as the punch descends and thereby pressing the sides of the grooved portion of the extension against the metal of the can and forming the spout-shaped hole in the can.

I claim:—

1. A can opener comprising a body having a comparatively wide upper portion and a narrow lower portion, a punch extending from said wide portion in a direction approximately parallel with the direction in which the narrow portion extends from the wide portion, said punch having a pointed free end, said narrow portion of the body having a boss extending toward said punch, the surface of said boss next the punch having a vertically extending groove.

2. A can opener comprising a body having a comparatively wide upper portion and a narrow lower portion a punch extending from said wide portion in a direction approximately parallel with the direction in which the narrow portion extends from the wide portion but curved slightly outward, said punch having a pointed free end, said narrow portion of the body having a boss extending toward said punch, the surface of said boss next the punch having a vertically extending groove.

3. A can opener comprising a conical pointed punch for penetrating the top of the can, means for slidably engaging the adjacent side of the can below the point of the punch and means for holding said punch and engaging means in rigid relation to each other, whereby, with the descent of the punch, its conical surface swages outward the adjacent side of the can into a rounded pouring spout.

T. IKEMORI.
